CLAIM

The ornamental design for an apparatus to refill tobacco paper, as shown and described.

DESCRIPTION

FIG. 1 is a top front right side perspective view of an apparatus to refill tobacco paper, showing my new design;
 FIG. 2 is a bottom rear left side elevational view thereof;
 FIG. 3 is a top plan view thereof;
 FIG. 4 is a bottom plan view thereof;
 FIG. 5 is a left side elevational view thereof;
 FIG. 6 is a right side elevational view thereof;
 FIG. 7 is a front view thereof; and,
 FIG. 8 is a rear view thereof.
